MINIATURE GASOLINE ENGINE

Daniel Miller, Montebello, Calif.

Application October 4, 1944, Serial No. 557,133

15 Claims. (Cl. 123—59)

1

My invention relates to miniature internal combustion motors, and relates in particular to a small gas engine especially suitable for powering model aircraft.

It is an object of my present invention to provide an improved and practical construction for miniature gasoline engines wherein the parts may be economically formed so as to cooperate upon assembly in a structure which will give good performance and durability such that its period of use without need for repair or reconditioning will be extended.

It is an object of the invention to provide in this engine a simple crank case so formed that it may be used in a one cylinder engine construction or in a two cylinder engine construction. This feature of the invention enables a purchaser of the one cylinder engine to later convert it to a two cylinder engine by obtaining additional parts, or, if the user has the complete set of parts, he may, as desired, have available either a one cylinder engine or a two cylinder engine, depending upon the manner in which he assembles the cooperating parts.

A further object of the invention is to provide a simple shaft and crank construction for a miniature internal combustion engine. The invention makes possible the use of connecting rods which are complete in one piece for the reason that in assembling the engine, it is not necessary to separate the bearing structure at the crank end of the connecting rod in order to place the bearing at the crank end of the connecting rod on the cooperating crank pin.

A further object is to provide an internal combustion engine having a pair of crank cases and a nozzle means for connecting these crank cases in side by side relation, the connecting means providing a bearing opening for a crank shaft member having crank arms rigidly formed on the ends thereof for operative connection to crank pins which, when the engine parts are assembled, are disposed within the crank cases.

A further object of the invention is to provide in a miniature aircraft construction a simple arrangement whereby the fuel mixture is fed into the crank cases, from which it is conveyed to the cylinders.

A further object of the invention is to provide a simple distributor and means for operating the same.

Further objects and advantages of the invention will be brought out in the following part of the specification.

2

Referring to the drawings which are for illustrative purposes only,

Fig. 1 is a plan view of my invention embodied in a single cylinder engine.

Fig. 2 is a view taken from the position indicated by the line 2—2 of Fig. 1.

Fig. 3 is an enlarged fragmentary sectional view taken as indicated by the line 3—3 of Fig. 2.

Fig. 4 is an enlarged fragmentary section taken 10 as indicated by the line 4—4 of Fig. 3.

Fig. 5 is a section taken as indicated by the line 5—5 of Fig. 3.

Fig. 6 is a section taken as indicated by the line 6—6 of Fig. 3.

Fig. 7 is a partly sectioned view showing my invention embodied in a two cylinder engine.

Fig. 8 is a fragmentary section taken as indicated by the line 8—8 of Fig. 7.

As shown in Figs. 1 to 6 inclusive, my invention 20 includes a cylinder 10 comprising a shell 11 which may be die cast from an aluminum alloy, this shell having therein a cylindric steel liner 12. The cylinder 10 has an exhaust port 13 on one side thereof and an inlet port 14 on its opposite side, which communicates through a passage 15 with the interior of a crank case 16, in accordance with two cycle gas engine practice. The shell 11 includes circular fins 17 around the upper portion thereof and parallel fins 18 projecting upwardly 30 from the top wall 19 of the shell 11, these parallel fins being disposed in diagonal relation to the longitudinal axis of the engine, as shown in Fig. 1. Being thus disposed, the fins 18 are all in angular relation to the line or direction of movement of the engine when the aircraft is in flight so that the side walls of all of these fins 18 are brought into forceful contact with the air and an improved cooling result is attained for the head of the cylinder.

40 The crank case 16, which is secured to the lower end of the cylinder 10 by means of screws 20 defines a crank chamber 21, surrounded by a circular wall 22. The front side of the crank case 16 has a large circular opening 23 therein and 45 the rear side of the crank chamber 21 is closed by a wall 24, from which a distributor shaft support 25 projects, this distributor shaft support having an axial opening 26 which communicates with the crank chamber 21. A crank shaft support 27 is bolted against the front of the crank case 16 by bolts 28 in a position to close the opening 23. The support 27 has a shaft opening 29, preferably lined with a steel or brass tube 30, to provide a bearing for the crank shaft 31. The support 27 is provided with a fuel inlet opening 32,

enclosed in part by an inlet tube 33. A gasoline inlet tube 34 extends diametrically across the tube 33 and has therein an orifice 35, the flow through which is controlled by a needle valve 36 which projects inward from a cap 37 threaded onto the projecting end 38 of the tube 34. The opposite end 39 of the tube 34 is adapted to be connected by means of a tube 40, as shown in Fig. 4, to a gasoline supply, whereby the gasoline, under control of the needle valve 36, may be fed through the orifice 35 into the air stream passing through the fuel inlet passage 32. A handle 41 is attached to the cap 37 to rotate the same, whereby the position of the needle valve 36 may be adjusted.

A piston 42 is slidable in the cylinder 10. This piston 42 has a pin 43 which passes through the opening 44 in the upper end of a connecting rod 45. The lower end of the connecting rod 45 projects into the crank chamber 21 and has a continuous annular wall or hub 46 defining a crank pin opening 47 for the lower end of the connecting rod 45. The rear end of the hub 46 has therein a circumferential groove 48 providing an annular shoulder.

The crank shaft 31 has on its inner end a crank member 49 of such size that it may be moved through the opening 23 of the crank case 16 into the crank chamber 21, the crank member 49 having a crank pin 50 which projects through the opening 47 at the lower end of the connecting rod 45. The projecting end 51 of the crank shaft 31 has a squared portion 52 to receive a propeller mounting plate 53, and a threaded portion 54 which projects through the propeller 55 and receives thereon a dome nut 56, as shown in Fig. 7. The hub 57 of the plate 53 is formed so as to comprise a cam to actuate a breaker arm 58 which is mounted on a plate 59 having a hub 60 which is clamped around a projecting portion of the support 21. For example, the hub 60 may surround the projecting end of the bearing sleeve 30 as shown in Fig. 7. Rotation of the plate 59 on the axis of the shaft 31 provides adjustment for advancing or retarding the opening of the breaker points 61, one of which is mounted on the arm 58 and the other of which is mounted on the plate 59. A thrust bearing 62 is disposed between the support 21 and the crank member 49.

A distributor shaft 63 extends through the shaft opening 26. On the other end of this distributor shaft 63 there is a body of insulating material 64 and on the inner end of the shaft 63 there is a lever 65 constructed of thin metal and having at its end a fork 66 which straddles the rearwardly projecting portion of the hub 46 and engages the annular groove 48. The revolution of the crank pin 50 around the axis of the shaft 31 is transmitted through the hub 46 to the lever 65 to produce rotation of the distributor shaft 63 and the distributor body 64 which is mounted on the outer end thereof. A distributor case 68 of insulating material is secured against the rearward face of the crank case 16 in a position surrounding the rotatable body 64. The case 68 consists of a cup having a shoulder 69 to engage the cylindric wall 70 which projects rearward as a part of the crank case 16, and the cup 68 is held in position by a pair of spring clips 71, the opposite ends of which engage openings 72 in the wall 70, and openings 73 in the end of the case 68 near its outer wall. In the center of the case 68 there is a connector screw 74, the inner end of which engages a metal distributor arm 75 which is mounted on the distributor body 64 so as to extend around one pe-

ripheral portion thereof. To cooperate with the member 75, the case 68 carries diametrically opposed screws 76 to which high tension circuit wires may be connected, it being understood that for a single cylinder engine, only one of these screws 76 is employed for connection to the single spark plug 77, then used, both of the screws 76 being employed when the distributor cap is used in the two cylinder assembly, shown in Fig. 7.

In the two cylinder arrangement shown in Fig. 7, the cylinder 10, crank case 16, connecting rod 45, distributor shaft 63, lever 65, and distributor mechanism, including the case 68, are employed. Also, the shaft 31 is employed with the associated breaker point mechanism and propeller mounting means previously described. A second cylinder 10' is provided, which is of the same form and construction as the cylinder 10. To this cylinder 10' a crank case 16' is attached, this crank case 16' having an opening 23' which faces and is spaced from the opening 23 of the crank case 16. The crank case 16' has a shaft opening 29 which is lined with the bearing sleeve 30 and the shaft 31 is extended through the opening 30 so that its crank member 49 will lie within the crank chamber 21' of the crank case 16' and its crank pin 50 will pass through the crank pin opening 47' of a connecting rod 45' which extends from the crank chamber 21' into the cylinder 10' to engage the piston 42 therein. The crank cases 16 and 16' are connected by a crank case connecting member 78 having a shaft opening 79 aligned with the shaft opening 29 to receive the shaft portion 80 of a crank shaft member 81 which has on its leftward or front end a crank arm 82 and has on its rear end a crank member 83 which is similar to the crank member 49 and has a crank pin 84 to project through the opening 47 in the lower end of the connecting rod 45. The connecting member 78 is split longitudinally thereof so that the shaft portion 80 of the crank shaft member 81 may be placed in the shaft opening 79, or, in other words, so that the connecting member 78 may be assembled around the shaft portion 81, since the shaft portion 81 cannot be moved axially into and through the opening 79 due to the enlargement on its end.

In accordance with the foregoing, the connecting member 78 is separable on the plane A—A, Fig. 8, so that it consists of a section 85 and a section 86 arranged so that they will meet on the plane A—A, and having cooperative laterally extending plate portions 87 which meet on the plane A—A and may be connected together by screws 88. The connecting member 78 has flanges 89 at the ends thereof to engage the crank cases 16 and 16' and close the openings 23 and 23' thereof when the crank cases 16 and 16' are clamped against the ends of the connecting member 78 by means of bolts 90.

The crank shaft member 81 has axial openings 91 leading in from the opposite ends thereof to intake ports 92 which are faced laterally in opposite directions. The upper section 85 of the connecting member 78 has therein a pair of inlet passages 93 to cooperate respectively with the ports 92 as the crank shaft member 81 rotates. A fuel inlet member 94, connected to the top of the upper section 85, defines an inlet chamber 95 which communicates with the passages 93, and has an air inlet tube 96 leading thereto, also a transverse gasoline inlet tube 34 transversing the tube 96 in the manner described with relation to the gasoline inlet tube 34 of Fig. 4, and its

relation to the air inlet tube 33, this gasoline inlet tube 34 having a needle valve 36 of the character shown in detail in Fig. 4.

The crank arm 82 of the crank shaft member 81 is provided with means whereby it may have operative connection with the crank pin 45', whereby rotation produced by the operation of the piston 42 in the cylinder 10 may be carried from the crank pin 84 through the crank pin 45 to the power output shaft 31 of Fig. 7, in addition to the power which this output shaft 31 receives from the piston 42 operating in the cylinders 10'. The crank arm 82 has means of coengagement with the crank member 49 represented by an opening 97 in the crank member 82, which receives the projecting end of the pin 50.

The simple assembly shown in Fig. 7, accordingly, does not employ a continuous rigid crank shaft extended through the several crank chambers, but instead has a sectional crank shaft consisting of the crank shaft member 81 and the output shaft 31 with detachable means of engagement between them, so that both of these parts 31 and 81 act as a single unit when the simple engine structure is assembled in the manner previously described. Furthermore, the arrangement shown does not require split bearings for the connecting rods, but the connecting rod bearings are simply formed by continuous, integral, annular walls at the ends of the connecting rods defining bearing openings through which the pins 43, 45', and 84 may be passed, as a part of the assembly operation.

I claim as my invention:

1. In an internal combustion engine, the combination of: first and second body members in side by side relation, each consisting of a cylinder and a crank case; a piston in each of said cylinders and a connecting rod extending from each piston into the cooperating crank case; an interconnecting crank shaft member extending from one of said crank cases to the other, said crank shaft member having a shaft portion with a first crank arm at one end thereof in the crank case of said first body and a crank member at the other end thereof in the crank case of said second body member; interconnecting means to connect said crank cases together having a shaft opening to receive said shaft portion, said means having a removable part to expose said shaft opening to one side so that said shaft portion may be placed in said shaft opening from the side of said interconnecting means; an output shaft extending into the crank case of said first body member in alignment with said shaft portion, said output shaft having a second crank arm spaced from said first crank arm; crank pin means connecting said first and second crank arms, said crank pin means engaging one of said connecting rods and being disengageable from one of said crank arms; and crank pin means on said crank member engaging the connecting rod in the crank case of said second body member.

2. In an internal combustion engine, the combination of: first and second body members in side by side relation, each consisting of a cylinder and a crank case; a piston in each of said cylinders and a connecting rod extending from each piston into the cooperating crank case; an interconnecting crank shaft member extending from one of said crank cases to the other, said crank shaft member having a shaft portion with a first crank arm at one end thereof in the case of said first body and a crank member at the other end thereof in the case of said second body member;

interconnecting means to connect said crank cases together comprising members separable along a longitudinal plane, there being a longitudinal shaft opening between said separable members into which said shaft portion may be placed by lateral movement; an output shaft extending into the crank case of said first body member in alignment with said shaft portion, said output shaft having a second crank arm spaced from said first crank arm; crank pin means connecting said first and second crank arms and one of said connecting rods and being disengageable from one of said crank arms; and crank pin means providing engagement between said crank member and the connecting rod in the crank case of said second body member.

3. In an internal combustion engine, the combination of: first and second body members in side by side relation, each consisting of a cylinder and a crank case; a piston in each of said cylinders and a connecting rod extending from each piston into the cooperating crank case; an interconnecting crank shaft member extending from one of said crank cases to the other, said crank shaft member having a shaft portion with a first crank arm at one end thereof in the case of said first body member and a crank member at the other end thereof in the case of said second body member; interconnecting means to connect said crank cases together comprising members separable along a longitudinal plane, there being a longitudinal shaft opening between said separable members into which said shaft portion may be placed by lateral movement; an output shaft extending into the crank case of said first body member in alignment with said shaft portion, said output shaft having a second crank arm spaced from said first crank arm; crank pin means connecting said first and second crank arms and one of said connecting rods; and crank pin means providing engagement between said crank member and the connecting rod in the crank case of said second body member.

4. In an internal combustion engine, the combination of: first and second body members in side by side relation, each consisting of a cylinder and a crank case, said crank cases having lateral openings faced toward each other; a piston in each of said cylinders and a connecting rod extending from each piston into the cooperating crank case; an interconnecting crank shaft member extending from one of said crank cases to the other, said crank shaft member having a shaft portion with a first crank arm at one end thereof in the case of said first body member and a crank member at the other end thereof in the case of said second body member; interconnecting means extending from one of said lateral openings to the other to connect said crank cases together having a shaft opening to receive said shaft portion, said means having a removable part to expose said shaft opening to one side so that said shaft portion may be placed in said shaft opening from the side of said interconnecting means; an output shaft extending into the crank case of said first body member in alignment with said shaft portion, said output shaft having a second crank arm spaced from said first crank arm; crank pin means connecting said first and second crank arms and one of said connecting rods and being disengageable from one of said crank arms; and crank pin means providing engagement between said crank member and the connecting rod in the crank case of said second body member.

5. In an internal combustion engine, the combination of: first and second body members in side by side relation, each consisting of a cylinder and a crank case, said crank cases having lateral openings faced toward each other; a piston in each of said cylinders and a connecting rod extending from each piston into the cooperating crank case; an interconnecting crank shaft member extending from one of said crank cases to the other, said crank shaft member having a shaft portion with a first crank arm at one end thereof in the case of said first body member and a crank member at the other end thereof in the case of said second body member; interconnecting means extending from one of said lateral openings to the other to connect said crank cases together comprising members separable along a longitudinal plane, there being a longitudinal shaft opening between said separable members into which said shaft portion may be placed by lateral movement; screw means to secure said crank cases to the ends of said interconnecting means; an output shaft extending into the crank case of said first body member in alignment with said shaft portion, said output shaft having a second crank arm spaced from said first crank arm; crank pin means connecting said first and second crank arms and one of said connecting rods and being disengageable from one of said crank arms; and crank pin means providing engagement between said crank member and the connecting rod in the crank case of said second member.

6. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases, said connecting rods having pin openings at the lower ends thereof; an interconnecting crank member having a shaft portion extending from one of said crank cases to the other, said shaft portion having in said first crank case a crank arm with a pin opening therein and having in said second crank case a crank member having a crank pin extending into the pin opening of the connecting rod which extends into said second crank case; interconnecting means to connect said crank cases together having a shaft opening to receive said shaft portion and a separate part extending from end to end thereof whereby said shaft opening may be exposed along one side so that said shaft portion may be placed therein; and an output shaft extending into said first crank case in alignment with said shaft portion, said output shaft having a crank member in said first crank case with a crank pin disposed so as to project through the pin opening of the connecting rod which extends into said first crank case and into the pin opening of said crank arm.

7. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases, said connecting rods having pin openings at the lower ends thereof; an interconnecting crank member having a shaft portion extending from one of said crank cases to the other, said shaft portion having in said first crank case a crank arm with a pin opening therein and having in said second

5 crank case a crank member having a crank pin extending into the pin opening of the connecting rod which extends into said second crank case; interconnecting means to connect said crank cases together having a shaft opening to receive said shaft portion and a separable part extending from end to end thereof whereby said shaft opening may be exposed along one side so that said shaft portion may be placed therein; an output shaft extending into said first crank case in alignment with said shaft portion, said output shaft having a crank member in said first crank case with a crank pin disposed so as to project through the pin opening of the connecting rod which extends into said first crank case and into the pin opening of said crank arm; a distributor shaft extending into said second crank case in alignment with said shaft portion; a distributor operated by the outer end of said distributor shaft; and a lever on the inner end of said distributor shaft arranged to be driven by the rotation of the crank member in said second crank case.

8. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases, said connecting rods having pin openings at the lower ends thereof; an interconnecting crank member having a shaft portion extending from one of said crank cases to the other, said shaft portion having in said first crank case a crank arm with a pin opening therein and having in said second crank case a crank member having a crank pin extending into the pin opening of the connecting rod which extends into said second crank case; interconnecting means to connect said crank cases together having a shaft opening to receive said shaft portion and a separable part extending from end to end thereof whereby said shaft opening may be exposed along one side so that said shaft portion may be placed therein; an output shaft extending into said first crank case in alignment with said shaft portion, said output shaft having a crank member in said first crank case with a crank pin disposed so as to project through the pin opening of the connecting rod which extends into said first crank case and into the pin opening of said crank arm; a distributor shaft extending into said second crank case in alignment with said shaft portion; a distributor operated by the outer end of said distributor shaft; and a lever on the inner end of said distributor shaft having a fork engaging the hub of the connecting rod which extends into said second crank case so as to be rotated by the rotation of the crank member therein.

9. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases, said connecting rods having pin openings at the lower ends thereof; an interconnecting crank member having a shaft portion extending from one of said crank cases to the other, said shaft portion having in said first crank case a crank arm with a pin opening therein and having in said second crank case a crank member having

a crank pin extending into the pin opening of the connecting rod which extends into said second crank case; interconnecting means to connect said crank cases together, comprising a first half and a second half engaging on a median longitudinal plane and being cooperatively chambered so that when they are placed on opposite sides of said shaft portion, they will form around said shaft portion a shaft opening in which said shaft portion is supported, means connecting the two halves together to form a unit, and means for connecting the ends of said interconnecting means to said crank case; and an output shaft extending into said first crank case in alignment with said shaft portion, said output shaft having a crank member in said first crank case with a crank pin disposed so as to project through the pin opening of the connecting rod which extends into said first crank case and into the pin opening of said crank arm.

10. In an internal combustion engine of the character described, the combination of: a cylinder; a crank case connected to the lower end of said cylinder, said crank case having a crank opening in the front wall thereof, and a distributor shaft opening in the rear wall thereof substantially aligned with said crank opening; a piston in said cylinder; a connecting rod extending from said piston into said crank case, said rod having a pin opening at its lower end and a hub projecting toward the rear wall of the crank case; a crank member of a size to pass from the exterior of said crank case through said crank opening into said crank case; a crank pin on said crank member extending through said opening of said rod; a shaft extending outward from said crank member; supporting means to support said shaft for rotation comprising a body having a wall to close said shaft opening and an opening through which said shaft may project into the exterior and providing bearing means to support said shaft; means to secure said supporting means to said crank case; a distributor shaft projecting through said shaft opening; and a lever on the inner end of said distributor shaft engaging said hub of said connecting rod so as to be rotated in response to rotation of said crank member.

11. In an internal combustion engine of the character described, the combination of: a cylinder; a crank case connected to the lower end of said cylinder, said crank case having a crank opening in the front wall thereof, and a distributor shaft opening in the rear wall thereof substantially aligned with said crank opening; a piston in said cylinder; a connecting rod extending from said piston into said crank case, said rod having a pin opening at its lower end and a hub projecting toward the rear wall of the crank case, said hub having an annular groove therearound; a crank member of a size to pass from the exterior of said crank case through said crank opening into said crank case; a crank pin on said crank member extending through said opening of said rod; a shaft extending outward from said crank member; supporting means to support said shaft for rotation comprising a body having a wall to close said shaft opening and an opening through which said shaft may project into the exterior and providing bearing means to support said shaft; means to secure said supporting means to said crank case; a distributor shaft projecting through said shaft opening; and a lever on the inner end of said distributor shaft having a fork at the end thereof to engage said groove of said

hub so as to be rotated in response to rotation of said crank member.

12. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases, said connecting rods having pin openings at the lower ends thereof; an interconnecting crank member having a shaft portion extending from one of said crank cases to the other, there being fuel passages extending into said shaft portion from the ends thereof with ports at their inner ends faced laterally in opposite directions, said shaft portion having in said first crank case a crank arm with a pin opening therein and having in said second crank case a crank member having a crank pin extending into the pin opening of the connecting rod which extends into said second crank case; interconnecting means to connect said crank cases together having a shaft opening to receive said shaft portion and a separable part extending from end to end thereof whereby said shaft opening may be exposed along one side so that said shaft portion may be placed therein, said interconnecting means having a fuel inlet port in the side wall thereof positioned so as to connect alternately with said ports of said shaft portion; a fuel and air mixing means connected to said fuel inlet port; and an output shaft extending into said first crank case in alignment with said shaft portion, said output shaft having a crank member in said first crank case with a crank pin disposed so as to project through the pin opening of the connecting rod which extends into said first crank case and into the pin opening of said crank arm.

13. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases; an interconnecting crank member having a shaft portion extending from one of said crank cases to the other, there being fuel passages extending into said shaft portion from the ends thereof with ports at their inner ends faced laterally in opposite directions, said shaft portion having in said first and second crank cases crank means engaging the lower ends of said connecting rods; interconnecting means to connect said crank cases together having a shaft opening to receive said shaft portion and a separable part extending from end to end thereof whereby said shaft opening may be exposed along one side so that said shaft portion may be placed therein, said interconnecting means having a fuel inlet port in the side wall thereof positioned so as to connect alternately with said ports of said shaft portion; and an output shaft extending into said first crank case in alignment with said shaft portion, said output shaft having a crank member in said first crank case connected to one of the crank members of said interconnecting crank member.

14. In an internal combustion engine, the combination of: first and second body members in side by side relation, comprising a first crank case with a connected cylinder and a second crank case with a connected cylinder; a piston in each of said cylinders and connecting rods extending from said cylinders into said crank cases,

11

said connecting rods having pin openings at the lower ends thereof; an interconnecting crank member having a shaft portion extending from one of said crank cases to the other, there being fuel passages extending into said shaft portion from the ends thereof with ports at their inner ends faced laterally in opposite directions, said shaft portion having in said first and second crank cases crank means engaging the openings in the lower ends of said connecting rods; interconnecting means to connect said crank cases together having a shaft opening extending from end to end thereof to receive said shaft portion, said interconnecting means having a fuel inlet port in the side wall thereof positioned so as to connect alternately with said port of said shaft portion; and an output shaft extending into said first crank case in alignment with said shaft portion, said output shaft having a crank member in said first crank case connected to one of the crank members of said interconnecting crank member.

15. In an internal combustion engine having first and second crank cases in side by side relation, cylinders connected to said crank cases, 25

12

pistons operative in said cylinders, and connecting rods extending from said pistons into said crank cases, the combination of: an interconnecting crankshaft member having a shaft portion extending from one of said crank cases to the other, there being crank means connected to the shaft member for operating said connecting rods, and there being fuel passages extending into said shaft portion from the ends thereof with ports at the inner ends of said passages communicating with the side wall of said shaft portion; interconnecting means to connect said crank cases together, having a shaft opening to receive said shaft portion and a separable part extending from end to end thereof whereby said shaft opening may be exposed along one side so that said shaft portion may be placed therein, said interconnecting means having a fuel intake port in the side wall thereof formed so as to connect alternately with said ports of said shaft portion; and an output shaft extending into said first crank case having means for operatively connecting it to said crankshaft member.

DANIEL MILLER.
